PAPER HANGER'S BOARD

Daniel H. Wieslander, Portland, Maine

Application February 16, 1934, Serial No. 711,593

6 Claims. (Cl. 164—78)

This invention relates to a paper hanger's board, and has for its object to provide, in a manner as hereinafter set forth, a composite board of the class referred to for use in connection with the pasting and trimming of wall paper thereupon and which is so constructed to provide a permanent non-buckling smooth surface to trim on thereby enabling the cutting of a straighter edge, than would be the case when the trimming is carried out upon a paper hanger's board of wood, as the latter is caused to shrink or swell by climatic conditions. The result of the cutting of a straighter edge on the wall paper culminates in giving the paper hanger a better opportunity to butt the wall paper properly, and in this respect give the finished product a better appearance.

A further object of the invention is to provide, in a manner as hereinafter set forth, a paper hanger's board formed of a metallic and a non-metallic section. The metallic section forms a non-buckling smooth surface for trimming purposes flush with the top surface of the other section and is so set up to overcome the presence of sharp metallic edge or edges to catch the straight edge when moved or to tear the wall paper on.

A further object of the invention is to provide, in a manner as hereinafter set forth, a paper hanger's board formed of a non-metallic section and a metallic section providing a trimming surface and slidably interengaging with and flush with the top surface of the non-metallic section, the metallic section being free of connection to the other section by nails or brads, which will enable the paper hanger to efficiently trim the wall paper, after the pasting and folding is done, without moving the strip from the position in which the strip was pasted.

A further object of the invention is to provide, in a manner as hereinafter set forth, a paper hanger's board including a non-metallic body section and a metallic section coupled upon the body section in a manner, to give it a freedom of movement on its contraction and expansion or when the body section swells or shrinks due to temperature and weather changes, whereby the metallic section is prevented from buckling or twisting resulting in such metallic section laying flat and smooth upon the body section at all times.

A further object of the invention is to provide, in a manner as hereinafter set forth, a paper hanger's board formed of a non-metallic body section having slidably connected thereto and

mounted thereupon in flush relation therewith, a metallic section formed with its top surface flat and smooth throughout. The connection between the sections being free of nails, brads, rivets and screws which otherwise would interfere with the trimmer, and by providing the top surface of the metallic section smooth throughout it enables the paper hanger to use his trimmer without danger or injury to the keen edge of the trimmer blade. The composite board also provides for a step toward economy by enabling the use of the entire surface of the metallic section for trimming purposes; that such metallic section provides for the composite board to give longer service than a board formed solely of wood; and further the metallic section need not be replaced so often as it is unusually durable for the purpose intended therefor.

A further object of the invention is to provide, in a manner as hereinafter set forth, a paper hanger's board formed of a non-metallic body section and a metallic trimming section interengaging with and flush with the top of the body section. The metallic section is of such form and slidably connected to the body section in a manner whereby it may be reversed and then positioned relative to the body section without any particular effort. Further the metallic section when worn or damaged may be quickly removed from the body section and a new one substituted without changing the form of the body section in any manner.

Further objects of the invention are to provide, in a manner as hereinafter set forth, a composite paper hanger's board which is simple in its construction and arrangement, strong, durable, compact, readily assembled, thoroughly efficient for the purpose intended thereby and comparatively inexpensive to manufacture.

To the above ends essentially and to others which may hereinafter appear, the invention consists of such parts, and such combination of parts which fall within the scope of the invention as claimed.

In the drawing:

Figure 1 is a fragmentary view in top plan of the paper hanger's board in accordance with this invention looking towards one end and one side thereof.

Figure 2 is a view similar to Figure 1 of the body section of the board.

Figure 3 is a fragmentary view in perspective of the metallic section of the board.

Figure 4 is a section on line 4—4 Figure 1,

Figure 5 is a section on line 5—5 Figure 1, and

Figure 6 is a top plan view of the board broken away.

The board includes a body section and a trimming section indicated generally at 7, 8 respectively.

The body section 7 is of non-metallic material, preferably wood and is of the desired width and length. As shown by way of example, the body section 7 consists of a pair of end bars 9, 10 and a panel 11 which may be formed of a plurality of units or a single unit and is illustrated by way of example as set up from a single unit. The bars 9, 10 correspond in length to the width of and are positioned at the ends of panel 11. The bars and panel have a tongue and grooved connection therebetween, as indicated at 12, 12' (Figure 4). The bars and panel are flush with each other. The section 7 is formed of two parallel lengthwise stretches 13, 14 (Figure 5). The stretch 13 is of greater width and of greater height than stretch 14 (Figures 2 and 5). The stretches 13, 14 have their lower faces flush with each other. The stretch 14 is formed at the inner side of its upper face with a rabbet which provides the stretch 13 with an inner side edge portion 15. The rabbet is of the same length as and forms the stretch 14 with a ledge 16 which merges into the inner side of stretch 13 at the bottom of edge portion 15. The rabbet also forms the stretch 14 with a shoulder 17 which is spaced from the edge portion 15 of stretch 13. Positioned upon ledge 16, abutting shoulder 17, flush with the upper face of stretch 14, spaced from the edge portion 15 and flush with the ends of stretch 14 is a bar 18 which forms in connection with the ledge 16 and edge portion 15 a vertical groove 19 (Figure 2) of a length corresponding to the length and opening at each end and at the upper face of the board. The bar 18 is of rectangular contour in transverse section. The bar 18 is anchored upon the ledge 16 by holdfast devices 20, and has that portion of its lower face bordering the bottom or inner end of the groove 19 rabbeted to form in connection with ledge 16 an inner horizontal groove 21 (Figure 2) corresponding in length to that of and opening at each end of the board. The groove 21 is of greater width than and extends at right angles to and opens into the inner end or bottom of groove 19. The outer side or lengthwise edge 22 of the stretch 14 is formed with an outer horizontal groove 23 which is spaced from the groove 21. The groove 23 corresponds in length to that of edge 22, opens at each end of the board and is disposed at the lengthwise center of edge 22. The groove 23 is arranged in alignment with groove 21.

The metallic section 8 which has its top face forming a smooth trimming surface consists of a metallic plate 24 preferably zinc. The plate 24 is formed of an oblong part 25 corresponding in length to that of the board and of a width corresponding to the combined width of the top faces of the stretch 14 and bar 18. Depending from each side of the part 25 is a flange. The flanges are of angle-shaped cross section, oppositely disposed and indicated at 26, 27. The flange 26 is formed of a vertical leg 28 and a horizontal leg 29 extending inwardly at right angles to and from the lower end of leg 28. The flange 27 is formed of a vertical leg 30 and a horizontal leg 31 extending inwardly at right angles to and from the lower end of leg 30. The leg 29 extends towards and is arranged in alignment with the leg 31. The upper face of part 25 is flush with the upper face

of stretch 13. The leg 28 rides against the upper portion of edge 22. The leg 29 is slidably mounted in groove 23. The leg 30 is arranged in groove 19. The leg 31 is slidably mounted in groove 21. The flanges 26, 27 slidably connect the metallic section 8 to the body section 7. The section 8 may be interengaged with section 7 from each side thereof. When the sections 7, 8 are set up relatively to each other, the ends of one section are flush with the ends of the other section. Both ends of the flange 26 may be bent slightly inward to arrest the shifting of section 8 relative to section 7, as indicated at 32 Figure 1.

What I claim is:—

1. A paper hanger's board comprising a non-metallic body section formed of a pair of lengthwise stretches corresponding in length to that of said section, one of said stretches being of greater width than that of the other, and a metallic section mounted upon and of the same length and width as the other of said stretches, said metallic section being flush with the top face of said stretch of greatest width, said stretch of smallest width being formed with spaced parallel horizontal grooves and a vertical groove opening at its lower end into one of said horizontal grooves, and said metallic section being formed with spaced parallel oppositely disposed flanges of angle-shaped cross section engaging in said grooves for slidably connecting said sections together. 90

2. A paper hanger's board comprising a non-metallic body section formed of a pair of parallel lengthwise extending stretches coextensive with the length thereof, one of said stretches being of greater thickness than the other to provide said section with an intermediate edge portion lengthwise thereof, a metallic section mounted upon and corresponding in length to the stretch of reduced thickness and flush with the upper face of the stretch of greater thickness, means arranged within and secured to the stretch of reduced thickness, opposing said edge portion in spaced relation and providing in connection with said edge portion and the stretch of reduced thickness a vertical groove and an inner horizontal groove, said body section having one of its outer lengthwise edges formed with an outer horizontal groove, and said metallic section being formed at its sides with oppositely disposed depending angle-shaped flanges, one of said flanges having a part opposing the said lengthwise edge and a part extended into the outer horizontal groove and the other having a part arranged in said vertical groove and a part extended into said inner horizontal groove. 105

3. A paper hanger's board comprising a non-metallic body section formed of a pair of parallel lengthwise extending stretches coextensive with the length thereof, one of said stretches being of greater thickness than the other to provide said section with an intermediate edge portion lengthwise thereof, a metallic section mounted upon and corresponding in length to the stretch of reduced thickness and flush with the upper face of the stretch of greater thickness, means arranged within and secured to the stretch of reduced thickness, opposing said edge portion in spaced relation and providing in connection with said edge portion and the stretch of reduced thickness a vertical groove and an inner horizontal groove opening into the bottom of said vertical groove, said body section having one of its outer lengthwise edges formed with an outer horizontal groove, and said metallic section being 110

- formed at its sides with oppositely disposed depending angle-shaped flanges, one of said flanges having a part opposing the said lengthwise edge and a part extended into the outer horizontal 5 groove and the other having a part arranged in said vertical groove and a part extended into said inner horizontal groove, and one of said flanges having portions thereof coacting with portions of said lengthwise edge for arresting the 10 shifting of said metallic section relative to said other section. 80
4. A paper hanger's board comprising a non-metallic body section formed of a pair of parallel lengthwise extending stretches coextensive with 15 the length thereof, one of said stretches being of greater thickness than the other to provide said section with an intermediate edge portion lengthwise thereof, a metallic section mounted upon and corresponding in length to the stretch 20 of reduced thickness and flush with the upper face of the stretch of greater thickness, means arranged within and secured to the stretch of reduced thickness, opposing said edge portion in spaced relation and providing in connection 25 with said edge portion and the stretch of reduced thickness a vertical groove and an inner horizontal groove opening into the bottom of said vertical groove, said body section having one of its outer lengthwise edges formed with an outer 30 horizontal groove, and said metallic section being formed at its sides with oppositely disposed depending angle-shaped flanges, one of said flanges having a part opposing the said lengthwise edge and a part extended into the outer horizontal 35 groove and the other having a part arranged in said vertical groove and a part extended into said inner horizontal groove, and the said vertical and that horizontal groove opening into the vertical groove being arranged between the 40 lengthwise center of said non-metallic section and the said lengthwise edge. 90
5. A paper hanger's board comprising a non-metallic section formed between its lengthwise edges with a vertical groove opening at its upper 45 face and an inner horizontal groove opening into the bottom of said vertical groove, said groove corresponding in length to that of said section, said section being formed in one of its lengthwise edges with an outer horizontal groove cor- 100
- responding in length to that of said edge, said section having that part thereof extending from said vertical groove to the said longitudinal edge of reduced thickness throughout with respect to the remaining part of said section, and a metallic section mounted upon said part of reduced thickness, flush with the upper face of the said other part and of the same length as that of the non-metallic section, said metallic section being provided at its sides with oppositely disposed angle-shaped flanges one of said flanges having a part opposing the said lengthwise edge and a part extended into said inner horizontal groove. 105
6. A paper hanger's board comprising a non-metallic section formed between its lengthwise edges with a vertical groove opening at its upper face and an inner horizontal groove opening into the bottom of said vertical groove, said groove corresponding in length to that of said section, said section being formed in one of its lengthwise edges with an outer horizontal groove corresponding in length to that of said edge, said section having that part thereof extending from said vertical groove to the said longitudinal edge of reduced thickness throughout with respect to the remaining part of said section, and a metallic section mounted upon said part of reduced thickness, flush with the upper face of the said other part and of the same length as that of the non-metallic section, said metallic section being provided at its sides with oppositely disposed angle-shaped flanges one of said flanges having a part opposing the said lengthwise edge and a part extended into said inner horizontal groove, said part of reduced thickness of said non-metallic section being of less width than that of the remaining part of such section, and one of said flanges having spaced portions coacting with spaced portions of said lengthwise edge to prevent the shifting of said sections relatively to each other. 110
